Patented Jan. 29, 1918.

UNITED STATES PATENT OFFICE.

SAMUEL T. CASTLEMAN, OF LOUISVILLE, KENTUCKY, ASSIGNOR TO LONG LIFE LUMBER COMPANY, INCORPORATED, OF LOUISVILLE, KENTUCKY, A CORPORATION OF KENTUCKY.

TANK OR TROUGH CONSTRUCTION.

1,255,078.

Specification of Letters Patent. Patented Jan. 29, 1918.

Application filed May 8, 1917. Serial No. 167,344.

To all whom it may concern:

Be it known that I, SAMUEL T. CASTLEMAN, a citizen of the United States, residing at Louisville, in the county of Jefferson 5 and State of Kentucky, have invented certain new and useful Improvements in Tank or Trough Constructions; and I do hereby declare the following to be a full, clear, and exact description of the invention, such as 10 will enable others skilled in the art to which it appertains to make and use the same.

This invention relates to tank or trough constructions; and it relates more particularly to a stock watering tank or trough of 15 wood or the like, composed of sections or parts which can be readily fitted together, without the exercise of special skill, to provide a substantially water tight receptacle, and capable also of being easily taken apart 20 when it is desired to transport the receptacle in knocked down condition.

For many purposes, and especially in connection with military operations, it is necessary to provide troughs for watering horses, 25 cattle, etc., and to so construct such troughs that they can easily be taken apart and transported from place to place. The separate parts or members of which such a trough is built up should be flat so that they 30 can be packed into small compass; and they should be of such character that no special skill is required to fit them together rapidly to provide a practically water tight receptacle of solid and substantial construction. 35 So far as I am aware, no thoroughly satisfactory tank or trough answering this description has heretofore been available; and it is a principal purpose of the present invention to supply this need.

40 The invention will first be explained in connection with the accompanying drawings, which illustrate a typical embodiment of the broad principles involved, and will then be more particularly pointed out in the 45 claims. In the drawings:

Figure 1 shows in elevational perspective a wooden watering trough constructed in accordance with the invention;

Fig. 2 is a transverse section on a larger 50 scale; and

Figs. 3 and 4 are sectional details on a still larger scale, illustrating the method of assembling the bottom and side planks to form tight joints.

Referring to the drawings, the watering 55 trough therein shown is constructed of wooden planks which have most desirably been creosoted for the double purpose of preventing the wood from swelling by absorbing moisture, and of discouraging stock 60 from cribbing the trough. The trough proper, designated generally by 10, is supported on a stout framework 11, and all parts of the trough and its supporting framework are held together by means of 65 threaded rods or bolts and nuts as shown, the use of nails being undesirable. As shown in Fig. 1, the sides 12 and bottom 13 of the trough are of tongue and groove construction; and the ends 14, and also the stiffening 70 partition 15, where a partition is employed, may be similarly constructed. An opening 15° in the partition provides communication between the two trough compartments. In the example illustrated, the sides, bottom, 75 ends and partition are each made up of three planks, each of the middle planks 12^a, 13^a and 14^a, having its opposite edges grooved as indicated at 16, to receive coöperating tongues provided on the mating edges of 80 the adjacent planks. For a purpose to be presently explained, the inner faces of said middle planks in the sides, ends and bottom, are slightly wider than the outer faces, 85 the grooved longitudinal edges of said middle planks being therefore cut on a slight bevel instead of square. This is shown clearly in Figs. 2 to 4, for the sides and bottom, and these figures also show in detail the manner of holding the bottom and side 90 planks together by means of bolts or tie rods 17. The under edge of the lowest board of each side is best cut at a slightly greater bevel than would be necessitated by the natural outward slope of the sides. Furthermore the under edge of the lowest board of each end is best slightly beveled so that the inner face of each of such lowest end boards 95 is a trifle wider than the outer face. The ends 14 being generally similar in construction to the sides 12, though substantially vertical instead of flaring outwardly like the sides, it appears unnecessary to illustrate the end construction in greater detail. The bolts 17 extend very loosely through holes 100 18 bored through said planks from edge to edge. Those joining the planks of the sides, ends and partition extend also through the 105

trough bottom, nuts 19 working on the threaded upper ends of the bolts or rods and serving to secure the parts in position.

In setting up the trough shown in the drawings the planks forming the bottom section are first assembled with the aid of the tie rods or bolts 17, and nuts 19. This section when thus assembled assumes an arched or warped form as shown in Fig. 4, due to the beveled edges of the middle plank 13^a. The bottom is now laid convex side up on the supporting framework, resting directly on cross-pieces 11^a thereof, and the end, partition, and side sections are placed in position on the bottom, the bolts of these sections extending through the bottom and through members 11^a. Horizontal tie rods 20, which may be substantially similar to rods 17, and which coöperate with exterior flat bearing plates 21 and angular pieces 22, which latter may simply be pieces of angle iron, are positioned just outside of each end 14, and serve to hold the side sections in place. For the same purpose additional horizontal tie rods 23 are provided adjacent the partition 15. When the trough sections are preliminarily assembled, as described, the side and end sections, as well as the bottom section, naturally assume an inwardly convex contour by reason of the described method of beveling the edges of certain of their component planks. If now the outer faces of the end sections be given a sharp blow, the end sections flatten out and slip into mortises 24 provided in the inner faces of side sections near their ends. The nuts, on all the tie rods may now be fully tightened up, whereupon the rectilinear lower edges of the ends and partition are drawn down upon the bottom section so as to flatten the latter out into the position shown in Figs. 1 and 2 and in dotted lines in Fig. 4. Similarly, the side sections are drawn tightly against the rectilinear lateral edges of the ends and partition, the side sections being thus finally flattened out as shown in Figs. 1 and 2, and in dotted lines in Fig. 3.

It will be noted that the effect of flattening out the side and bottom sections from the arched position shown in full lines in Figs. 3 and 4 is to develop very intense localized pressure along the inner portion of the joints between the middle planks and the planks adjoining them, thus sealing the joints. The same thing is of course true for the end sections. A similar effect is produced where the beveled lower edges of the side and end sections abut against the bottom. On the other hand, the outer portions of the joints are under much less pressure, and may even be slightly opened as indicated at *w*, Figs. 1, 2 and 3, the extent of such opening being more or less exaggerated in the drawings for purposes of ex-

planation. The flattening out of the sections from their original convex or warped position is evidently similar in effect to the action of a powerful toggle, in insuring tight joints. The described tongue and groove construction is especially useful in this connection because it not only facilitates properly matching up the planks, but it also maintains them in accurate registry at all times, insuring the development of sealing pressure at the desired points.

In order to avoid any mistake in putting the trough together hurriedly, it is of advantage to leave the outer faces of the planks rough and to plane the inner faces smooth; but this is not essential, of course.

Various changes in details of construction can be made without departing from the spirit of the invention, and such changes are contemplated in the appended claims. Moreover, it is not intended to limit the invention to a container in which all the sections or walls are constructed in the manner above described, although such a construction is most desirable. Evidently the benefits of the invention can be realized to some extent where less than all the sections are of the character herein disclosed. It is to be noted also that although, in the specific example here given, the sealing pressure is developed substantially at the inner face of each section, nevertheless the component planks may be beveled in a manner opposite to that above prescribed so that the sealing pressure may be developed adjacent the outer faces of the sections. This latter method of construction is not ordinarily so desirable as that illustrated in the drawings. It is evident that assembling means other than the described tie rods or bolts may be employed, though the latter are convenient and efficient.

What I claim is:

1. A tank or trough having a wall comprising a plurality of planks in edge-to-edge engagement, the edges of the planks being so formed that the said wall tends to arch, means securing said planks together, and means tending to flatten out the arch, thereby maintaining a tight joint between the planks.

2. A collapsible watering trough comprising substantially plane side walls, ends, and bottom with substantially rectilinear edges, said side walls and bottom being composed of planks, having their abutting edges so formed that when matched the planks tend to lie in different planes, assembling means holding the bottom planks together, assembling means holding the side wall planks together and to the bottom, and means drawing the trough ends, side walls and bottom together in such manner that said side walls and bottom are maintained substantially plane against the opposing

tendency of said assembling means, whereby tight joints are secured.

3. A collapsible watering trough comprising side walls, ends, and bottom, said side walls and bottom each consisting of a plurality of planks fitted together by tongues and grooves, at least one of said planks having its edges beveled so that the planks tend to lie in different planes, bolts extending loosely through each set of planks and drawing them together, and means drawing said side walls, ends and bottom together in such manner as to maintain them substantially plane and water-tight.
- 10 4. A container consisting of a plurality of sections, at least one of said sections comprising a plurality of flat members assembled in edge-to-edge engagement, the joints between said members being of such character that such section tends naturally to assume a warped contour, securing means

25 preventing said members from separating but permitting limited relative transverse movement thereof, and means arranged to hold said section in proper relation to the other container sections and to flatten said section out against the opposing tendency of said securing means, thereby producing a concentrated pressure or pinch over a localized portion of each of said joints.

30 5. In a container a wall comprising a plurality of planks arranged edge to edge and securing means for holding them together, the plank edges being so formed that said wall tends to warp under the action of said securing means, and means resisting such warping, whereby tight joints between said planks are attained.

35 In testimony whereof I hereunto affix my signature.

SAMUEL T. CASTLEMAN.
